ORBIN W. LIVINGSTON, OF SCHENECTADY, NEW YORK, ASSIGNOR TO GENERAL ELECTRIC COMPANY, A CORPORATION OF NEW YORK

CONTROL SYSTEM

Application filed September 11, 1931. Serial No. 562,359.

This invention relates to control systems, more particularly to regulating systems, and it has for an object the provision of a simple, reliable and improved system of the kind.

More specifically the invention relates to regulating systems in which the regulated characteristic of a circuit is controlled by means of electric valve apparatus, and accordingly a further object of this invention is the improvement and simplification of the circuit arrangement and apparatus employed to control the valves.

Still more specifically the invention relates to voltage regulating systems in which the voltage of a circuit is subject to wide variations from a desired value responsively to changes in some operating condition of the circuit, such as the load, and a further object of this invention is the provision of an improved voltage regulating system in which electric valves are employed to maintain the voltage of a translating circuit substantially constant at a desired value.

Although not limited in its application the invention is particularly advantageous in connection with systems in which the voltage of a translating circuit is controlled by means of a variable series connected current limiting device such for example as a theatre dimming system in which the intensity of lamp illumination of the various lamp circuits is controlled by series connected impedances, such as variable resistances or reactances. In such a system it is desirable especially in connection with the presetting of scenes, that the intensity of illumination of a lamp circuit will accurately correspond with the indication of a control device employed to vary the illumination. The voltage drop across the series impedance device changes, however, with changes in the lamp load, and consequently the position of the indicator is not always an accurate indication of the degree of illumination.

As an example, let it be assumed that the usual or normal number of lamps are connected in circuit and that the control device is actuated to a position indicating fifty per cent of full brilliancy. If the number

of lamps in circuit is now decreased one-half, the voltage drop across the series impedance device will decrease proportionately and consequently the lamp voltage and brilliancy will increase to a value that is 55 considerably greater than the fifty per cent indicated by the indicating device. Similarly if the lamp load is doubled, the voltage drop across the series impedance will be correspondingly increased with the result 60 that the lamp voltage and brilliancy will decrease to a value less than that indicated. As previously pointed out, this undesirable characteristic renders the presetting of scenes exceptionally difficult since the operator of the system can not, with any reasonable degree of accuracy, predetermine the brilliancy of a circuit for widely differing lamp loads, and this necessitates final adjustment of the intensity of illumination 70 after the scene has been switched on.

In prior systems this difficulty was partially overcome by utilizing specially designed saturable reactors which due to the special design and construction were very 75 expensive.

Accordingly an object of this invention is the provision of a control system in which means are provided for adjusting and maintaining the lamp voltage substantially constant at any desired value within a wide range of lamp load. An advantage of the invention is that a very inexpensive type of reactor may be utilized instead of the expensive specially designed reactors heretofore employed and since the reactor is the most expensive item in the circuit and a separate reactor is required for each circuit, the cost of the entire system is greatly reduced. A further advantage of the invention is that although the cost of the system is greatly reduced the operating characteristics of the system are greatly improved.

In carrying the invention into effect in one form thereof, a control device is employed to control an operating condition of an electric circuit, and this device is controlled responsively to the difference of a control voltage and a voltage derived from the controlled circuit. More specifically, an 100

electric valve provided with a control electrode is employed to vary the reactance of a saturable reactor connected in circuit relationship with the controlled circuit and this valve is in turn controlled by supplying to the control electrode a control voltage, and a regulating voltage derived from the controlled circuit and of opposite polarity to that of the control voltage. This control voltage is variable to provide for adjusting the regulated characteristics to a desired value and the regulating voltage is preferably pulsating direct current for the purpose of facilitating its utilization to vary 10 the bias of the control electrode.

In illustrating this invention in one form thereof it is shown as embodied in a theatre dimming system and as utilized therein for controlling the intensity of illumination of 20 a lamp circuit. However, as previously pointed out the invention is not limited in its application and it is merely shown as embodied in a theatre dimming system because due to the simplicity of the circuits 25 and apparatus involved, this type of system is particularly adapted for the purposes of illustration and facilitating an understanding of the invention.

For a better and more complete understanding of the invention reference should 30 now be had to the following specification and to the accompanying drawing in which Fig. 1 is a simple diagrammatical representation of an embodiment of the invention and Fig. 2 is a chart of curves employed to 35 explain and clarify the operation of the system of Fig. 1.

Referring now to the drawing a suitable 40 translating circuit including a translating device such as represented by the conductors 10, 11 and a plurality of lamps 12 is supplied from any suitable source such for example as the alternating current source represented by the conductors 13, 14. The voltage supplied to the lamp and the degree 45 of illumination thereof are controlled by means of an impedance device, illustrated in the drawing as a saturable core reactor 15, the reactance of which is controlled by suitable electric valve apparatus 16, the operation 50 of which in turn is controlled by a suitable source of control voltage 17 and a voltage derived from the load circuit 10, 11.

For the sake of simplicity the saturable 55 reactor 15 is shown conventionally in the drawing with the core member omitted. This reactor comprises a plurality of reactance windings 18, 19 each wound upon a 60 separate leg of the iron core and connected in series relationship between the supply source and the load. In the specific arrangement illustrated in the drawing the reactance windings 18, 19 are connected in 65 parallel relationship with each other and in

series relationship between the side 13 of the source and the lamp 12. The saturable reactor 15 is also provided with a control winding 20. Direct current of a variable magnitude is supplied to the control winding 20 by means of the electric valve apparatus 16, to the output circuit of which it is connected by means of a conductor 21. Any variation in the magnitude of the current flowing in the control winding 20 effects a corresponding change in the saturation of the reactor 15 and likewise in the reactive voltage drop across the reactance windings 18 and 19. Since the voltage of the source 13, 14 remains substantially constant, a variation in the reactive drop across the windings 18 and 19 effects a corresponding change in the voltage applied to the lamps 12 and consequently in the intensity of their illumination. It will thus be seen that a variation in the current flowing in the control winding 20 effects a corresponding change in the voltage applied to the lamp 12; an increase in the current resulting in a decrease in the reactive voltage drop across the reactance windings 18, 19 and an increase in the voltage applied to the lamp 12 whilst a decrease in the current results in an increase of the reactive drop across the windings 18, 19 and a decrease of the lamp voltage.

Although the electric valve apparatus 16 may be of any suitable type it is illustrated in the drawing as an electric discharge device, preferably of the three electrode type 100 into the envelope of which a small quantity of an inert gas such for example as mercury vapor is introduced after exhaust; the presence of the gas within the tube serving to change the usual pure electron discharge 105 into an arc stream constituting the tube a grid controlled arc rectifier. The electric discharge device 16 may be either a full wave or a half wave rectifying device; the half wave rectifying device being shown in the drawing for the purpose of illustration due to the simplicity of the necessary controlling circuits. As shown, the electric discharge device 16 is provided with an output electrode or anode 22, a control electrode or grid 23 and a filamentary cathode 24; the latter being heated to the necessary degree of incandescence by energy supplied to it from the secondary winding 25 of a 110 supply transformer the primary winding 26 of which is supplied with energy from any suitable source such as the alternating current source 13, 14 to which it is connected as illustrated. The anode 22 is connected to one side of the supply source over a circuit that may be traced through the conductor 21, the control winding 20 and conductor 26 to the side 14 of the supply 115 source.

Briefly stated the operation of the electric discharge device is as follows:

An alternating voltage is applied to the anode 22 from the source 13, 14 and this voltage is represented in Fig. 2 by the curve 27. Current will flow in the output circuit, if at all, only during that half cycle of anode voltage in which the potential of the anode is positive with respect to that of the cathode 24, that is, only during the half cycle of anode voltage represented by the portion of the curve 27 above the line 0—0. In order to start current flowing in the output circuit, the voltage of the grid 23 must be at the proper value, and this critical grid voltage, i. e., the voltage at which current will just start flowing in the anode circuit is represented in Fig. 2 by the dotted curve 28. Once current has started to flow in the output circuit it rises abruptly to a value that is limited only by the impedance of the output circuit and continues until the output circuit is interrupted or until the anode voltage is reduced to zero which 25 in the case of an alternating current happens when the curve 27 passes through the zero point. The grid has no control of the instantaneous value of the current in the output circuit but only has control over the 30 time in the cycle at which current starts to flow and it will thus be seen that if the voltage applied to the grid is either an alternating or an undulating voltage that the average value of the current flowing in the output 35 circuit may be controlled by shifting the phase of the grid voltage relative to that of the anode. When the grid voltage is exactly in phase with the anode voltage the current will begin to flow in the output 40 circuit at the beginning of the positive half cycle and will continue until the anode voltage again passes through zero whilst if the grid voltage is 180° out of phase with the anode voltage, current will not start to flow 45 in the output circuit at any time. For intermediate phase relationships, current will start flowing at proportionate intermediate points in the half cycle.

The grid bias voltage may be derived 50 from any suitable source 17 which is illustrated in the drawing as a variable potentiometer resistance one terminal of which is connected to the side 13 of the supply source by means of the conductor 29 and the other 55 terminal of which is connected to the opposite side of the supply source by means of the conductor 30. The potentiometer 17 is variable so that the control voltage supplied to the grid may be varied as desired 60 and a rectifying device 31 of any suitable type is included in the connections between the movable contact 32 of the potentiometer 17 and the point 33 in the grid circuit for the purpose of rectifying and applying a 65 direct current controlling voltage to the

grid. It will be seen, however, that the rectifying device 31 only rectifies one-half cycle of the voltage across the potentiometer 17. In order that this half-wave rectified voltage may be converted into a voltage of 70 constant magnitude a suitable filter device comprising a resistance 34 and a condenser 35 connected in parallel therewith are included in the grid circuit between the cathode and the point 33. It will be seen 75 that the cathode 24 is connected to the side 13 of the supply source by means of the conductor 36 and since the rectifying device 31 only rectifies the positive half cycle of the wave the voltage applied to the grid 23 is 80 positive with respect to the cathode voltage and is represented in Fig. 2 by the straight line 37 parallel to the axis 0—0.

A regulating voltage is derived from the voltage of the lamp circuit 10, 11 by means of the transformer 38 and is supplied to the grid 23 to which one terminal of the secondary winding of the transformer 38 is connected as illustrated. The opposite terminal of the secondary winding of the transformer 38 is connected to a second electrode of the rectifying device 31 and the polarity of the transformer winding is so chosen that the rectifying device 31 rectifies the inverse half-cycle of the lamp voltage wave, i. e., the half-cycle that is opposite from that which is rectified by the electric discharge device 16. A suitable filter device comprising a resistance 39 and a condenser 40 connected in parallel therewith is connected 90 in the grid circuit one terminal of the resistance 39 being connected to the terminal 33 of the resistance 34 and the opposite terminal of the resistance 39 being connected to one terminal of the secondary winding 100 of the transformer 38. The electrical constants of the resistance 39 and the condenser 40 are so chosen that the rectified voltage is slightly pulsating and the connections between the transformer 38, the rectifier 31 105 and the resistance 39 are so made that the terminal of the resistance 39 nearest the grid 23 is negative with respect to the point 33. This regulating voltage which is supplied to the grid 23 is represented in Fig. 2 by the 110 pulsating curve 40.

It will thus be seen that the controlling and regulating voltages are opposite in polarity with respect to the grid 23 and that, therefore, the actual or resultant grid voltage 120 is the difference between these two voltages and is represented in Fig. 2 by the dotted curve 41.

The potentiometer 17 is variable so that the magnitude of the control voltage can be 125 varied at the will of the operator and it will be clear by reference to Fig. 2 that if the magnitude of either the control voltage 37 or the regulating voltage 40 is changed this will result in either raising or lowering the 130

position of the actual grid voltage 41 which in turn will have the effect of shifting the phase relationship of the actual grid voltage with respect to the anode voltage and will thus effect a change in the current flowing in the output circuit of the electric discharge device 16.

Since the control voltage 37 is preferably a smooth direct current voltage it will be clear that this might be derived from a separate source of direct current voltage instead of from the alternating current source 13, 14. The arrangement shown in the drawing, however, is preferable in that it eliminates the expense of a separate source.

Since the saturable reactor 15 is highly inductive and since the electric discharge device 16 is shown as a half-wave rectifying device it will be clear that very little current will flow in the output circuit through the control winding 20 because during the inverse half cycle which the electric discharge device is not rectifying the inductance of the reactor 15 would force current back into the line 13, 14 unless some other suitable path were provided. If current were returned to the line 13, 14 during the inverse half cycle, the result would be that practically no direct current would flow in the control winding 20 and the reactive drop across the saturable reactor 15 could not be varied or controlled.

For the purpose, therefore, of maintaining the current flow in the control winding during the inverse half cycle, a suitable half-wave rectifying device 42 is connected in parallel with the control winding; the anode 43 being connected to the anode 22 of the electric discharge device 16 and the filamentary cathode 44 being connected to the distant terminal of the control winding 20 and heated to the necessary degree of incandescence by current supplied to it from the secondary winding 45 of the supply transformer. It will be seen that when the voltage applied to the anode 22 of electric discharge device 16 from the line becomes negative that the terminal of the control winding which is connected to the anode tends to remain positive due to the inductance of the reactor 15 and consequently will continue to flow from the anode 43 to the cathode 44 and to the opposite terminal of the control winding 20 until the voltage applied to the anode 22 from the line again becomes positive. As a result of sustaining the current flow in the control winding during the inverse half cycle this current is substantially a direct current of constant but adjustable magnitude.

With the above understanding of the apparatus and connections comprising an embodiment of the invention the operation will be readily grasped and easily understood from the description which follows:

When the movable contact 32 of the variable potentiometer 17 is in the right-hand or zero position the control voltage applied to the grid 23 of electric discharge device 16 is zero and as a result the phase relationship of the actual grid voltage relative to the anode voltage is such that the electric discharge device 16 causes very little current to flow in the control winding 20 with the result that the reactive drop across the windings 18, 19 is large and the lamp voltage is very small; so small in fact that the lamps are dark.

By moving the movable contact 32 to an intermediate position on the potentiometer 17 the control voltage applied to the grid 23 is increased to some positive value, such for example as that represented by the straight line 37 in Fig. 2. The phase relationship of the actual grid voltage relative to the anode voltage is thereupon suddenly changed to a position in which the grid voltage is substantially in phase with the anode voltage 27 and as a result electric discharge device 16 allows a large current to flow in the control winding 20 thus reducing the reactive drop across the saturable reactor 15 and increasing the lamp voltage. However, as the lamp voltage is increased in magnitude the regulating voltage represented by the curve 40 is likewise increased which results in shifting the phase of the actual grid voltage relative to the anode voltage toward the right to a position in which a balance is established between the positive control voltage and the negative regulating voltage.

If the movable contact 32 is moved to the extreme left-hand position, the magnitude of the control voltage 37 is further increased in a positive direction which results in shifting the phase of the actual grid voltage further to the left to a position in phase with the anode voltage as a result of which the current in the control winding becomes maximum, the reactive drop across the saturable reactor 15 becomes minimum, and the voltage applied to the lamps 12 becomes maximum and the lamps burn at maximum brilliancy.

In order to obtain the regulating action it is of course necessary for some condition such, for example, as the load of the lamp circuit to change. As an example let it be assumed that the movable contact of the potentiometer has been moved by the operator to the mid-position in which it is illustrated in the drawing which indicates that if the normal or usual number of lamps are connected in the circuit 10, 11 the lamps will be illuminated at approximately fifty per cent brilliancy. Let it also be assumed that the operator desires only to have one-half the usual or normal number of lamps in circuit and that the lamp load is reduced by one-half. This reduction in the lamp

load effects a corresponding reduction in translating device such, for example, as an electric motor and that the control winding 20 might be any control device such, for example, as the field winding of an electric motor or the field winding of a Ward Leonard generator employed to supply any suitable translating device.

Although in accordance with the provisions of the patent statutes I have described this invention as embodied in concrete form, it should be understood that the invention is not limited to the precise apparatus or exact connections shown in the drawing since these are merely illustrative and modifications and alterations will readily suggest themselves to persons skilled in the art without departing from the true spirit of this invention or from the scope of the annexed claims.

What I claim as new and desire to secure by Letters Patent of the United States is:

1. A control system comprising in combination an alternating current load circuit, control means for said circuit comprising electric valve apparatus provided with a control grid, means for supplying a variable direct current control voltage to said grid, and means comprising a rectifying device energized from said alternating current load circuit for supplying to said grid a regulating voltage having a direct current component of opposite polarity with respect to said control voltage.

2. A control system comprising in combination an alternating current load circuit, a variable impedance device for controlling the voltage of said circuit, means for varying the impedance of said device comprising electric valve apparatus provided with a control grid, means for supplying a variable direct current control voltage to said grid, and means comprising a rectifying device energized from said alternating current load circuit and connected in circuit with said grid so as to supply thereto a regulating voltage having a direct current component of opposite polarity with respect to said control voltage.

3. A control system comprising an alternating current load circuit, control means for said circuit comprising electric valve apparatus provided with a control grid, and means for supplying a pulsating direct current voltage to said grid comprising a filter device connected in circuit with said grid, means for supplying a direct current control voltage to said grid, and a rectifying device energized from said alternating current load circuit and connected to said grid so as to supply thereto a regulating voltage having a direct current component of opposite polarity with respect to said control voltage.

4. A control system comprising an alternating current load circuit, a variable re-

Similarly if the lamp load is doubled, the reactive drop across the saturable reactor 15 is increased and the lamp voltage decreased to a value that is lower than the value indicated by the position of the movable contact 32 on its indicating device. A decrease in the lamp voltage, however, results in a decrease in the magnitude of the regulating voltage 40 with a resultant shift toward the left of the actual grid voltage, thereby effecting an increase in the current flowing in the control winding 20, a decrease in the reactive drop of the saturable reactor 15 and an increase in the lamp voltage. As before the actual grid voltage continues to shift until a balanced relationship between the regulating voltage and the control voltage is reestablished at which time the lamp voltage will be such that the intensity of illumination is at the value indicated by the position of the movable contact 32 of the potentiometer 17.

It will thus be seen that by this invention the lamp voltage and consequently the intensity of illumination of the lamp is regulated and maintained substantially constant at any desired value quite independently of the lamp load and that the operator can thus be assured that the intensity of illumination of the lamp will accurately correspond with the position of the movable contact 32 as indicated upon the associated indicating device independently of the number of lamps in circuit.

As previously pointed out, this invention is not limited in its application to a theatre dimming system since it will be clear that the lamp load might be replaced by any

- actance device for controlling the voltage of said circuit, means for varying the reactance of said device comprising electric valve apparatus comprising a control grid, and 5 means for supplying a variable phase pulsating direct current voltage to said grid comprising a filter device connected in circuit with said grid, a rectifying device energized from said alternating current circuit and connected to said grid for supplying 10 a voltage thereto having a direct current component and means for supplying a variable direct current control voltage of opposite polarity to said grid.
- 15 5. In a control system, a source of alternating current, a load device supplied from said source, a variable reactance device included in circuit with said load device for controlling the voltage thereof, a direct current source of control voltage, means for deriving a voltage from said load, and an electric valve controlled by said control voltage and said derived voltage for controlling 20 said reactance device.
- 25 6. In a control system for theatre dimming apparatus and the like, a lamp circuit, an impedance device for controlling the voltage of said circuit, a source of control voltage and means controlled by said lamp voltage and said control voltage for controlling 30 said impedance device.
7. A control system for theatre dimming apparatus and the like comprising a lamp circuit, a variable impedance device included in said circuit for controlling the voltage thereof, a source of control voltage, means for deriving a voltage from said lamp circuit, and an electric valve responsive to the difference of said control voltage and said 40 derived voltage for varying the impedance of said impedance device.
- 45 8. A control system comprising in combination, an alternating current translating circuit, means for controlling an operating condition of said circuit comprising an electric valve provided with a control grid, means for supplying a bias to said grid, and means responsive to said operating condition for supplying a slightly pulsating bias of opposite polarity to said grid.
- 50 9. In a control system, a load, means for supplying alternating voltage to said load; and means for maintaining the voltage of said load substantially constant at a desired value comprising an electric valve provided with a control grid, means for supplying a variable direct current bias to said grid, and means responsive to said load voltage for supplying a slightly pulsating bias of opposite polarity to said grid comprising a filter device connected in circuit with said grid and a rectifying device energized from said alternating load voltage and connected to said grid.
- 55 10. A control system comprising in combination, a source of supply, a translating circuit supplied from said source; and means for adjusting and maintaining the voltage supplied to said circuit substantially constant at a desired value comprising an electric valve provided with a control grid, means for supplying a bias to said grid, means responsive to the voltage of said circuit for supplying to said grid a bias of opposite polarity, and means for varying said first mentioned bias.
- 60 11. In a control system, a source of alternating current, a load circuit supplied from said source, means for controlling an operating condition of said circuit comprising an electric valve energized from said source and provided with a control grid, and phase shifting means for energizing said grid comprising a source of bias voltage for said grid and means responsive to variations in said operating condition for supplying to said grid a pulsating bias of opposite polarity.
- 65 12. In a control system, a source of alternating current, a circuit including a variable load supplied from said source, means for controlling the voltage of said load comprising an electric valve energized from said source and provided with a control grid, and phase shifting means for energizing said grid comprising a variable source of bias and means responsive to variations in said load for supplying to said grid a pulsating bias of opposite polarity.
- 70 13. A control system comprising a source of alternating current, a translating circuit supplied from said source, means for varying the voltage supplied to said circuit comprising an electric valve energized from said source and provided with a control grid, and phase shifting means for energizing said grid comprising a source of direct current bias for said grid, and a rectifying device energized from said circuit and a filter device connected therewith for applying to said grid a pulsating bias of opposite polarity.
- 75 14. In a regulating system, a source of alternating current, a load supplied from said source, voltage control means for said load comprising a saturable reactor provided with a control winding, means for controlling the reactance of said reactor comprising an electric valve connected to said control winding and energized from said source, said valve being provided with a control grid, a variable potentiometer connected to said source, and means for applying a pulsating bias to said grid comprising a rectifying device connected to said potentiometer and to said load, and a filter device connected to said rectifying device and to said grid.
- 80 15. In a control system, a source of alternating current, a load supplied from said

source, voltage control means for said load comprising a variable saturable reactor connected in series relationship with said load and provided with a control winding, means for varying the reactance of said reactor comprising a half-wave rectifying electric valve energized from said source and connected to said control winding, said valve being provided with a control grid, a second valve connected to said control winding for sustaining the current flow during the inverse half-cycle, and phase shifting means for said grid comprising a rectifying device connected to said load and to said source for supplying to said grid a bias derived from the inverse half-cycle of said load voltage and a bias of opposite polarity, filter means for rendering said derived bias slightly pulsating and said opposite bias substantially non-pulsating, and a variable potentiometer for varying said opposite bias.

16. In a control system for theatre dimming apparatus and the like, a source of supply, a lamp circuit supplied from said source; and means for varying and maintaining the voltage supplied to said circuit substantially constant at a desired value, comprising an impedance device for controlling the voltage of said circuit, an electric valve provided with a control electrode for varying the impedance of said device, means for supplying a bias voltage to said electrode, means responsive to the voltage of said lamp circuit for supplying a bias voltage of opposite polarity to said electrode, and means for varying said first mentioned bias.

17. A control system for theatre dimming apparatus comprising an alternating current source, a lamp circuit supplied from said source, a variable reactance device for varying the voltage of said lamp circuit, means for varying the reactance of said device comprising an electric valve energized from said source and provided with a control grid, phase shifting means for energizing said grid comprising a source for supplying a bias to said grid, and means responsive to variations in the load of said circuit for supplying a variable bias of opposite polarity to said grid.

18. In a control system for theatre dimming apparatus and the like, a source of alternating current, a lamp circuit supplied from said source, a variable saturable reactor included in said circuit for varying the voltage thereof, means for varying the reactance of said reactor comprising an electric valve energized from said source and provided with a control grid, phase shifting means for energizing said grid comprising a source for supplying a bias to said grid, means responsive to the voltage of said circuit for supplying to said grid a pulsat-

ing bias of opposite polarity and having a variable magnitude proportional to said lamp circuit voltage, and a variable potentiometer for varying said first mentioned bias.

19. A control system for theatre dimming apparatus comprising a source of alternating current, a lamp circuit supplied from said source, means for varying the voltage of said circuit comprising a saturable reactor provided with a control winding, means for varying the reactance of said reactor comprising an electric valve energized from said source and connected to said control winding, said valve being provided with a control grid, and phase shifting means for energizing said grid comprising a source of grid bias voltage, a variable potentiometer for varying said bias voltage, and means comprising a half-wave rectifying device energized from said lamp circuit and a filter device connected to said rectifying device for applying to said grid a pulsating bias voltage of opposite polarity to said first mentioned bias and proportional to said lamp voltage.

In witness whereof, I have hereunto set my hand.
